UNITED STATES PATENT OFFICE.

ARTHUR L. LUCAS, OF SLATER, MISSOURI.

HAY-RACK BRACKET.

No. 913,744.

Specification of Letters Patent.

Patented March 2, 1909.

Application filed December 26, 1907. Serial No. 408,097.

To all whom it may concern:

Be it known that I, ARTHUR L. LUCAS, citizen of the United States, residing at Slater, in the county of Saline and State of Missouri, 5 have invented certain new and useful Improvements in Hay-Rack Brackets, of which the following is a specification.

The present invention relates to certain new and useful improvements in the construction of brackets of that type which are designed to be applied to a wagon box for the purpose of extending the sides thereof upwardly and outwardly.

The primary object of the invention is to 15 provide a strong and durable bracket which can be quickly and easily applied to the vehicle box or removed therefrom as may be found desirable.

The invention further contemplates novel 20 means for connecting corresponding brackets upon opposite sides of the wagon so as to relieve the sides thereof from strain when the wagon is heavily loaded.

For a full description of the invention and 25 the merits thereof and also to acquire a knowledge of the details of construction and the means for effecting the result, reference is to be had to the following description and accompanying drawings, in which:

30 Figure 1 is a perspective view of a wagon body having the invention applied thereto. Fig. 2 is a transverse sectional view through the same. Fig. 3 is a detail view of one of the brackets, portions being broken away.

35 Corresponding and like parts are referred to in the following description and indicated in all the views of the drawings by the same reference characters.

The invention comprises essentially an approximately triangular bracket adapted to be 40 detachably applied to the side of a wagon box and formed with a clamping arm designed to fit over the upper edge of one of the sides of the wagon body.

45 The bracket proper is constituted by a pair of limbs 1 and 2 disposed at an obtuse angle to each other and connected by a diagonal brace 3, the lower limb 2 normally assuming a vertical position and fitting against 50 the outer face of the wagon side while the upper limb 1 extends outwardly and upwardly from the upper edge of the wagon side. For the purpose of holding this

bracket in position a clamping arm 4 is utilized, the said clamping arm being arranged 55 parallel to the lower limb 2 and being designed to fit over the edge of the wagon side.

Should the wagon be heavily loaded it is contemplated to relieve the sides from strain by connecting corresponding brackets upon 60 opposite sides of the wagon by means of a tie member, and for this purpose each of the brackets is provided with a vertical web portion at the junction of the clamping arm 4 and the limbs 1 and 2, the said web extending 65 for a short distance along the upper limb 1. The vertical web portion 5 upon each of the brackets is formed with a plurality of openings or perforations 6 any selected one of which is designed to engage a ring 7, the said 70 ring having a chain 8 connected thereto. The chains from corresponding brackets upon opposite sides of the vehicle body constitute the before mentioned tie member, and the free end of one of the said chains carries a hook 9 75 for engaging the opposite chain. It will be readily apparent that this construction admits of varying the effective length of the tie member as may be required for wagon boxes of different widths. 80

As shown in the present instance each of the limbs 1 and 2 of the bracket and the clamping arm 4 has a T section and comprises a lateral flange A reinforced by a stiffening rib B. It will also be observed that 85 the vertical web 5 constitutes an extension of the stiffening rib B of the clamping arm, such a construction admitting of the production of a rigid bracket with the use of a minimum amount of material. The upper limbs 90 1 of the brackets are designed to receive the usual boards or slats and are formed with the perforated ears 10 through which the fastening members extend by means of which the slats are secured in position. These 95 slats may be either spaced as in an ordinary hay rack, or may be placed close together and the wagon utilized for hauling corn, coal and the like.

Having thus described the invention, what 100 is claimed as new is:

A bracket of the character described, comprising members 1 and 2 arranged relatively at an obtuse angle, a brace 3 connecting said members, a clamping arm springing from 105 said members at the angle and extending

parallel with the member 2, and a web B extending along the outer side of the clamping arm, and provided at its upper end with an extension 5 passing over the clamping arm 5 and along the member 1 for a short distance, the upper portion of said extension 5 having a series of openings.

In testimony whereof I affix my signature in presence of two witnesses.

ARTHUR L. LUCAS. [L. s.]
